Nathan Price Chaney(57) **CLAIM**

The ornamental design of a triple groove concrete jointer, as shown and described.

DESCRIPTION

FIG. 1 is a perspective view of the triple groove concrete jointer of the invention.

FIG. 2 is a side view of the triple groove concrete jointer.

FIG. 3 is a front view of the triple groove concrete jointer.

FIG. 4 is a top view of the triple groove concrete jointer; and,

FIG. 5 is a bottom view of the triple groove concrete jointer.

The broken line portions of FIG. 1 are included for purposes of environment and form no part of the claimed design.

1 Claim, 3 Drawing Sheets4:
FIG.
